Int. Cl. D26—05

U.S. Cl. D48—20 E

FIG. 1 is a front view of a neck supported lamp showing my new design, the strap, table, and person being shown in dashed lines for illustrative purposes; the shade of the lamp being rotatable is shown in one position in FIG. 1 and in an alternate position in FIGS. 2-7;

FIG. 2 is a front elevational view on an enlarged scale with the shade thereof rotated into a different selected position relative to the other parts thereof;

FIG. 3 is a rear elevational view thereof on an enlarged scale;

FIG. 4 is a bottom plan view thereof on an enlarged scale;

FIG. 5 is a top plan view thereof on an enlarged scale;

FIG. 6 is an end elevational view thereof on an enlarged scale;

FIG. 7 is another end elevational view thereof on an enlarged scale; and

FIG. 8 is a view in section taken on the line 8-8 in FIG. 4.

I claim:
The ornamental design for a neck supported lamp, as shown and described.
